US0D1040142S

(12) **United States Design Patent** (10) **Patent No.:** **US D1,040,142 S**
(45) **Date of Patent:** **** Aug. 27, 2024**

(54) **EARPHONE**

(71) Applicant: **BEIJING XIAOMI MOBILE SOFTWARE CO., LTD.**, Beijing (CN)

(72) Inventor: **Yuhao Zhang**, Beijing (CN)

(73) Assignee: **Beijing Xiaomi Mobile Software Co., Ltd.**, Beijing (CN)

(**) Term: **15 Years**

(21) Appl. No.: **35/516,080**

(22) Filed: **Jan. 24, 2022**

(80) **Hague Agreement Data**

Int. Filing Date: **Jan. 24, 2022**
Int. Reg. No.: **DM/218739**
Int. Reg. Date: **Jan. 24, 2022**
Int. Reg. Pub. Date: **Jan. 27, 2023**

(30) **Foreign Application Priority Data**

Jul. 30, 2021 (CN) 202130492035.2

(51) **LOC (14) Cl.** **14-01**

(52) **U.S. Cl.**

USPC **D14/223**

(58) **Field of Classification Search**

USPC D14/137, 138, 155–159, 160–174,
D14/187–188, 189–199, 203.1–203.8,

(57) **CLAIM**

The ornamental design for an earphone, as shown and described.

DESCRIPTION

1. Earphone
2. Earphone
- 1.1 : Front
- 1.2 : Back
- 1.3 : Left
- 1.4 : Right
- 1.5 : Top
- 1.6 : Bottom
- 1.7 : Perspective
- 1.8 : Perspective
- 2.1 : Front
- 2.2 : Back
- 2.3 : Left
- 2.4 : Right

(Continued)

2.5 : Top**2.6** : Bottom**2.7** : Perspective**2.8** : Perspective

Reproductions **1.1-1.8** show a first embodiment of the earphone; and reproductions **2.1-2.8** show a second embodiment of the earphone.

The broken lines shown in the reproductions depict portions of the earphone that form no part of the claimed design.

1 Claim, 16 Drawing Sheets
